COUPLING FOR PIPES, PILES, AND LIKE ELEMENTS

Rudolf Mulder, Haarlem, Netherlands

Application December 4, 1945, Serial No. 632,635
In Germany August 5, 1944

2 Claims. (Cl. 287—54)

2

In the building of scaffolds and like constructions it is important that the coupling for pipes, piles or like elements to be interconnected and of which the scaffold is to be built up, consists of as few simple parts as possible, and that no use is made of parts such as wedges and like elements that are liable to get lost. The invention relates to a coupling which complies with these requirements.

According to the invention to this end the coupling is characterized by at least two straps detachably or rigidly interconnected, or being integral, and the two ends of which projecting beyond the pipe or the like to be embraced, are each provided with an opening, a clamping block being rotatable in each pair of openings, the clamping surface of said block being eccentric with respect to the axis of rotation in such a manner that the clamping force increases if the load increases. Preferably according to the invention each clamping piece is revolvable due to its axial displacement by reason of the fact that at its one end it is provided with a helical or like sliding surface which by sliding over an edge of the opening, that in the direction of axial displacement is the most remote, is revolved in the sense of clamping the clamping piece in a selflocking way.

Further according to the invention the corresponding edges of the holes of each strap may be located in planes intersecting one another at an acute angle, the one hole being wider than the other and the wider hole serving for the introduction of the clamping block until the helical or like sliding surface thereof will come to bear upon the sliding edge of the other opening, both holes having a circular bent wall portion on which a corresponding part of the clamping piece is turning when the latter is revolved.

This construction is very simple on account of its small number of parts; locking keys are no more necessary. Further the manipulation is easy and the clamping action faultless and selflocking.

Preferably each clamping piece is connected to the corresponding strap in such a manner that it may be removed from the pair of openings concerned. In this case the coupling does not have any loose parts.

The drawing illustrates the invention by an embodiment.

Fig. 1 shows a front elevation of a coupling according to the invention when applied to two pipes.

Fig. 2 is a rear view of the left coupling strap of Fig. 1.

Fig. 3 is a front elevation of a clamping block

Fig. 4 is a side- or end elevation thereof.

In Fig. 1 the pipes to be coupled are denoted

1 by 1 and 2; they cross each other perpendicularly. The coupling comprises two U-shaped straps 3 and 4 the webs of which are interengaging; the webs constitute the strap parts embracing the tubes directly. In the straps arms 5 and 6 of the right strap 3 which arms laterally project from said webs, and also in the strap arms of the left strap 4, the arm 7 only of which is visible in the front elevation, holes are provided which for each pair of arms of a strap are located opposite one another. These pairs of holes serve each to receive a clamping block 8 or 9 respectively that is rotatable and axially slideable therein. Each clamping block consists of a rod having the desired section and having a particular shape at the one end. In Fig. 1, on the left, the hole in the strap arm 7 is indicated by 10; the lower edge 11 of the hole in the drawing makes an acute angle with the lower edge 12 of the hole 21 in the rearmost strap arm 22 non-visible in Fig. 1 but shown in Fig. 2. The two lower edges 11 and 12 are thus located in planes intersecting one another at an acute angle and being perpendicular to the plane of the drawing.

25 The front hole 10 is wider than the rear hole 21. Each rod shaped clamping block (Figs. 3 and 4) at one end is provided with a helically shaped sliding surface 13 that at the one extremity of the clamping block is bounded by the tangent, passing from the centre of the eccentric edge of that extremity 14 up to the circle of rotation 17 (contact point 24), and by two lines, one of which begins at 14 and extends over the clamping surface of the clamping block and the other of which begins at 24 and extends over the flat side of the clamping block, which two lines meet each other at 16. The sliding surface 13 is adapted to co-operate with the lower edge 12 of the—in Fig. 1—rear hole 21 in such a manner that when the clamping block is axially displaced from the front to the rear, the lower edge 12 on account of its contact with the helical surface 13, sliding thereon, produces a rotation of the clamping block in the direction of the arrow (Figs. 1 and 2) resulting in a self-locking clamping of the eccentric clamping surface 15 against the pipe 2.

30 The clamping block is passed through the wide front hole 10 until the helical surface 13 will come to rest with its end upon the lower edge 12 of the rear hole 21. This hole just as the front hole 10 is provided with a circularly bent wall portion 23 on which the corresponding part of the clamping block will rotate; further the holes 10, 21 have such a shape that rotation of the clamping block on account of the cooperation of the helical sliding surface 13 with the lower edge 12 of the rearmost hole 21 is not interfered with, as will appear from the drawing. When the

clamping block has been placed in the above mentioned position with the helical surface 13 on the lower edge 12 of the rearmost hole 21, then during further driving in, e. g. by some hammer strokes, an automatic revolving of the clamping block is produced in the manner described above.

In the embodiment described above and illustrated in the drawing various structural modifications may be made within the spirit of the invention.

For instance the coupling instead of having one pipe supporting surface may have two supporting surfaces located in the longitudinal axis of the pipe.

Further the coupling according to the invention besides for pipes, piles and the like may be used advantageously for interconnecting other suitably shaped bodies or objects.

I claim:

1. A pipe support comprising a plurality of U-shaped straps interengaged at the closed ends thereof, each free end of each said strap having an opening therein and forming pairs of openings in each of said U-shaped straps, a clamping member extending through each said pair of openings for clamping a pipe therebetween and said U-shaped strap, said member comprising a bar having an eccentric clamping surface thereon, and a helical shaped sliding surface on an end thereof whereby upon entry of one said member in one said pair of openings said mem-

ber will be tilted by coaction of said helical sliding surface with an edge of one of said openings and provide a self-locking clamping of said pipe.

2. A pipe support as claimed in claim 1, an edge of one of said openings in each said pair being in a plane different from that of an edge in a coacting one of said pair of openings, the said planes of said edges intersecting at an acute angle, one of said openings in a pair being larger than the other said opening and serving for the introduction of said clamping member to the edge of the other said opening in a plane different from that of said larger opening, and said openings having curved wall portions, whereby said 15 clamping member is rotated in said curved wall portions during tilting thereof by said helical sliding surface.
